UNITED STATES PATENT OFFICE.

GEORGE M. EAMES AND JOHN S. FINCH, OF BRIDGEPORT, CONNECTICUT, ASSIGNEES
TO THE SINGER MANUFACTURING COMPANY, OF ELIZABETH, NEW JERSEY, A COR-
PORATION OF NEW JERSEY.

SEWING MACHINE.

Application filed November 10, 1921. Serial No. 514,181.

To all whom it may concern:

Be it known that we, GEORGE M. EAMES and JOHN S. FINCH, citizens of the United States, residing at Bridgeport, in the county of Fairfield and State of Connecticut, have invented certain new and useful Improvements in Sewing Machines, of which the following is a specification, reference being had therein to the accompanying drawings.

10 This invention relates to improvements in sewing machines and particularly to that class of sewing machines commonly designated hemstitching machine.

15 The primary object of this invention is to increase to a substantial degree the capability of high speed of operation of machines of this character and reduce to a substantial degree the vibrations particularly incident in sewing machines employing a laterally vibrating needle.

20 Other and more specific objects of the invention will be apparent from the following description and claims.

25 In its preferred embodiment, the present invention comprises a sewing machine having the usual cloth-plate and overhanging tubular bracket-arm in which latter is journaled the main-actuating shaft of the machine for imparting vertical reciprocatory movements to the needle. This main-shaft has belt-driving connections with a loop-taker actuating shaft and a feed-shaft journaled beneath the cloth-plate substantially parallel with and in the vertical plane containing the axis of rotation of the main-shaft. The feed-shaft is journaled in suitable bearings provided in the machine frame and carries actuating cams for imparting rising and falling as well as forward and backward feed-movements to the feed-dog. 30 This feed-shaft also carries an actuating cam beneath the cloth-plate which has operative connections with the needle-vibrating rod for laterally vibrating the needle. By 35 reason of the fact that this feed-shaft carries the several cams mentioned beneath the cloth-plate, vibration of the overhanging arm of the machine is considerably lessened over machines in which the feed-actuating 40 cams and the needle-vibrating cams are carried by the overhanging arm.

45 The feed-shaft is tubular and disposed within this shaft is the loop-taker actuat-

ing shaft rotating in the same direction as the feed-shaft. The loop-taker actuating shaft is journaled at one end within the rotating feed-shaft which journaling by reason of the shafts rotating in the same direction at different speeds considerably lessens the friction and distributes the wearing action of the loop-taker shaft throughout the journaling provided by the feed-shaft. The forward end of the loop-taker actuating shaft is connected by two-to-one gearing with a loop-taker rotatable upon a vertically disposed axis in the usual manner.

50 In the accompanying drawings, Fig. 1 is a front side sectional elevation of a machine embodying the present improvements. Fig. 2 is a bottom plan view of the same. Fig. 3 is a front end elevation of the machine with the face-plates removed. Fig. 4 is a sectional view substantially on the line $x-x$ of Fig. 2.

55 Referring to the drawings, the present machine comprises a cloth-plate 1 from which rises a hollow standard 2 of a tubular overhanging bracket-arm 3 terminating in a head 4. Suitably journaled in the overhanging arm is a main actuating shaft 5 carrying at one end a belt-pulley 6 and provided at its opposite end with the usual crank connected by means of a link 7 with a bar 8 journaled for vertical, reciprocatory movements in the head 4.

60 Secured by means of a screw 9 to the lower end of the bar 8 is a supporting bracket 10, carrying an angled piercer-holder 11 in which are secured, by means of set-screws, 12, the main and auxiliary piercers 13 and 14. Fulcrumed upon the bracket 10 by means of a pivot-screw 15 is an oscillatory auxiliary bracket 16 upon which is adjustably secured, by means of a screw 17, the shank of a socketed needle-clamp 18 suitably 65 carrying a needle 19. Suitably secured to the auxiliary bracket 16 and projecting upwardly therefrom is a needle-vibrating rod 20 of which the upper end is slidingly mounted in a swivel joint 21 carried by a 70 vibrating guide-bar 22. The guide-bar 22 is supported at its upper end for swinging movements upon a pivot-screw 23 threaded into a block 24 affording an upper bearing for the bar 8. To steady the swinging movements of the guide-bar 22, the lower end 75

105

thereof is provided with a guide-fin 25 entering a notch in a block 26 affording a lower bearing for the bar 8.

A needle-thread take-up 27 is fulcrumed upon the machine frame and is actuated from a slide-block 28 in the usual manner, while a presser-bar 29 is suitably journaled for endwise movements in the head 4 and carries yielding presser-feet, as 30.

10 Intermediate its ends, the guide-bar 22 has a ball-socket connection with one end of a pitman 31 of which the opposite end passes through an elongated slot 32 formed in a transverse boss 33 on the end of an arm 34.

15 Slidably fitted within a vertical aperture provided in the boss 33 is a swivel-pin 35 having an aperture, alined with the slot 32 and entered by the end of the pitman 31 secured therein by means of a set-screw 36.

20 It will be understood that endwise movement of the swivel-pin 35 is prevented by the engagement of the parallel walls of the slot 32 with the pitman 31, but that the pin is capable of a rocking movement limited by the length of the slot 32. The arm 34 is adjustably secured by means of a screw 37 within a radial guideway 38 provided in a head 39 suitably secured upon the upper end of a rock-shaft 40 journaled in vertically alined bearings provided in the machine frame.

25 The main actuating shaft 5 carries peripherally groove belt-pulleys 41 and 42. Pulley 41 is connected by means of a clip-belt 43 with a like grooved pulley 44, the hub of which latter is secured as by means of a set-screw 45 upon a tubular, feed-actuating shaft 46. The pulleys 41 and 44 are so proportioned that the feed-shaft 46 completes one

30 revolution in three revolutions of the main-shaft 5, the two shafts rotating in the same direction. Adjacent one end thereof, the feed-shaft 46 is journaled in a bushing 47 secured by a set-screw 48 in a bearing lug 49 provided on the machine frame, while at its opposite end this feed-shaft is journaled in a bushing 50. The bushing 50 is secured by a set-screw 51 in a gear-housing 52 attached to the machine frame by screws as 53.

35 50 Journaled at one end in the bushing 50 and adjacent its opposite end in an enlarged portion of the feed-shaft 46 is a loop-taker actuating shaft 54, concentric with said feed-shaft, but spaced therefrom excepting at the rearward end of the latter. This spacing provides a minimum of wearing surface and affords a lubricant receptacle between the two shafts. The actuating shaft 54 projects beyond the rearward end of the feed-shaft

40 55 60 65 46 and upon this projection is secured by set-screws as 55 the hub of a peripherally grooved pulley 56 which embraces the hub of the pulley 44. The pulley 56 is connected by means of a clip-belt 57 with the pulley

70 75 80 85 90 95 100 105 110 115 120 125 130 shaft 5 and the shaft 54 rotate uni-directionally and in the ratio of one to one. The hub of the pulley 56 abuts against the end of the actuating shaft 46, thereby preventing endwise movement of the shaft 54 in one direction while endwise movement in the opposite direction is prevented by the hub of a bevel-gear 58 suitably secured upon the end of the shaft 54 within the housing 52. It will be observed that a slight clearance is provided between the end face of the feed-shaft 46 and the bushing 50 to permit of movement of this bushing as may be necessary to properly adjust the bevel-gear 58.

The bevel-gear 58 meshes with a similar gear 59 secured upon a loop-taker carrying shaft 60 journaled in vertically alined bearings provided in the housing 52. At its upper end the shaft 60 carries a rotary loop-taker 61, the beak 62 of which rotates in a substantially horizontal plane and in the formation of lock-stitches coacts in the usual manner with the needle 19 to cast loops of the needle-thread around a mass of under thread within the path of travel of the beak 62. The loop-taker 61 is rotated twice for each rotation of the actuating shaft 54 and therefore of the main-shaft 5. At its lower end there is secured upon the shaft 60 a collar 63 having an eccentric portion 64 embraced by the strap of a pitman 65 for actuating a needle-guard 66. As this needle-guard forms the subject of a separate patent of John C. Ringe, No. 1,484,191, dated February 19, 1924 wherein the details of its construction and operation are fully set forth, it is not deemed necessary to herein make further reference thereto.

Secured upon the actuating shaft 46 by means of a set-screw 67 is a needle-vibrating cam 68 having a peripheral cam-groove 69 entered by a roller 70 carried by an arm 71 projecting laterally from the rock-shaft 40. This cam 68, through the described connections with the needle-vibrating rod 20, imparts the usual lateral movements to the needle 19 common to hemstitching machines, but by reason of the present location of this cam the vibrations of the overhanging arm are reduced to a minimum at high speed operation.

The actuating shaft 46 also carries feed-actuating cams 72 and 73, each suitably secured upon said shaft. The feed-cam 72 is provided on one face thereof with a cam-groove 74 entered by a cam-roller 75 carried by a vibratory arm 76. The vibratory arm 76 projects laterally from a fulcrum-shaft 77 journaled in a suitable bearing provided in a bracket 78 attached by screws, as 79, to the machine frame underneath the cloth-plate. Preferably formed integral with the vibratory arm 76 is a segmental guideway 80 in which is adjustably secured by means of a screw-bolt 81 a slide-block 82 connected

- with one end of a pitman 83 of which the other end is pivotally secured to a rock-arm 84 clamped to a feed-rocker shaft 85 journaled in suitable bearings provided on the machine frame. The feed-rocker shaft 85 carries spaced arms 86 between which is pivotally supported the transverse boss 87 of a feed-bar 88 carrying the usual feed-dog 89.
- 10 The feed-bar 88 is provided with a slide-way 90 entered by a slide-block 91 carried by a rock-arm 92 clamped to one end of a feed-lift rock-shaft 93 suitably journaled beneath the cloth-plate 1. The rock-shaft 93 at its other end has a vibratory arm 94 carrying a cam-roller 95 entering a cam-groove 96 provided in one face of the cam 73. The cam-grooves 74 and 96 are so formed as to respectively impart to the feed-dog 90 feed and feed-lift movements in relatively timed relation as to effect two forward and one backward feeding movement of the fabric for each hemstitch figure, i. e., during three successive work-penetrating movements of the needle 19. As the related movements of the needle and the feed-dog 90 to effect a hemstitch figure are well known in the art, it is not deemed necessary to herein repeat a description thereof.
- 20 Means is provided for conducting lubricant to the shafts 46 and 54. An inclined duct 97 provided in the standard 2 communicates with an enlarged opening 98 in the cloth-plate and in which opening is inserted some absorbent material. The lug 49 is provided with a duct 99 leading from the opening 98 to an aperture 100 in the bushing 47 to lubricate the feed-shaft bearing in the bushing. The bushing-aperture 100 communicates with an aperture 101 provided in the feed-shaft 46, whereby during revolutions of the shaft 46 lubricant may enter the interior thereof and be conducted through a slot 102 to lubricate the looper-shaft bearing in the feed-shaft.
- 25 The described construction and arrangement of the several parts has provided a hemstitching machine capable of a very substantial increase in speed of operation with less vibration and wear of the parts than was incident in machines of prior construction and at the same time has produced a comparatively quiet running machine.
- 30 Having thus set forth the nature of the invention, what we claim herein is—
1. In a sewing machine, the combination with a cloth-plate, a vertically reciprocating and laterally vibrating needle, means for imparting the vertical reciprocating movements to the needle, a rotary thread-mass carrying loop-taker complemental to said needle in the formation of lock-stitches, and a feed-dog, of a plurality of actuating shafts 70 journaled coaxially beneath said cloth-plate, brating movements to said needle, the rotary movements to the loop-taker and the feeding movements to the feed-dog from said actuating shafts.
2. In a sewing machine, the combination with a cloth-plate, a vertically reciprocating and laterally vibrating needle, means for imparting the vertically reciprocating movements to the needle, a rotary thread-mass carrying loop-taker complemental to said 75 needle in the formation of lock-stitches, and a feed-dog, of a plurality of actuating shafts journaled coaxially beneath said cloth-plate, means for actuating said loop-taker from one of said shafts, and means for imparting 80 the laterally vibrating movements to the needle and feeding movements to said feed-dog from the other of said shafts.
3. In a sewing machine, the combination with a cloth-plate, an overhanging arm, a 85 rotary shaft journaled in said overhanging arm, a needle, operative connections between said shaft and said needle for endwise reciprocating the latter, a rotary thread-mass carrying loop-taker complemental to the 90 needle in the formation of lock-stitches, and a feed-dog, of a feed-shaft journaled beneath said cloth-plate, a loop-taker actuating shaft journaled coaxially with said feed-shaft, and belt driving connections between 95 the rotary shaft and said feed-shaft, and between the rotary shaft and the loop-taker actuating shaft.
4. In a sewing machine, the combination with a cloth-plate, an overhanging arm, a 100 rotary shaft journaled in said overhanging arm, a needle, operative connections between said shaft and said needle for endwise reciprocating the latter, a loop-taker complemental to the needle in the formation of 105 stitches, and a feed-dog, of a plurality of actuating shafts substantially parallel to said rotary shaft journaled beneath said cloth-plate substantially in the vertical plane containing the axis of said rotary shaft, belt driving connections independent of each other between the rotary shaft and said actuating shafts for rotating the latter, and means for actuating the loop-taker and the feed-dog from said actuating shafts.
5. In a sewing machine, the combination with a cloth-plate, an overhanging arm, a 110 rotary shaft journaled in said overhanging arm, a needle, operative connections between said shaft and said needle for endwise reciprocating the latter, and a feed-dog, of a 115 feed-dog actuating shaft journaled beneath said cloth-plate substantially in the vertical plane containing the axis of rotation of said rotary-shaft, driving connections between said shafts including proportionate pulleys carried by said shafts and a pulley-connecting belt whereby the feed-actuating shaft rotates at one third the speed of rotation of 120 said rotary shaft, and operative connections 125
- 60 65 70 75 80 85 90 95 100 105 110 115 120 125 130
- 65 and means for imparting the laterally vi-

- between the feed-dog actuating shaft and the feed-dog for imparting to the latter fabric feeding movements.
6. In a sewing machine, in combination, a cloth-plate, a rotary main shaft, an end-wise reciprocating and laterally vibrating needle, operative connections intermediate said main shaft and the needle for endwise reciprocating the latter, a feed-dog, a feed-dog actuating shaft journaled beneath the cloth-plate, means for rotating said feed-dog actuating shaft from the main-shaft, operative connections for imparting both work-engaging and work-advancing movements to the feed-dog from said feed-dog actuating shaft, and operative connections between the feed-dog actuating shaft and said needle for laterally vibrating the latter.
7. In a sewing machine, the combination with a cloth-plate, a needle, means for end-wise reciprocating said needle, a loop-taker complementary to the needle in the formation of stitches, and a feed-dog, of loop-taker and feed-actuating shafts disposed coaxially beneath said cloth-plate, means for 25 rotating said shafts in a continuous direction at relatively different speeds and operative connections between the feed-dog actuating shaft and said feed-dog for imparting both feed and feed-lift movements to 30 the latter.

In testimony whereof, we have signed our names to this specification.

GEORGE M. EAMES.
JOHN S. FINCH.
